LATCH

William Schnell, Detroit, Mich., assignor to Ternstedt Manufacturing Company, Detroit, Mich., a corporation of Michigan

Application December 15, 1932
Serial No. 647,420

15 Claims. (Cl. 292—173)

This invention relates to a latch and more particularly that type of latch adapted for a refrigerator.

It is an object of this invention to produce a latch having a spring actuated bolt, the projecting end of which is provided with a roller having a supporting pin which is concealed.

This invention also contemplates a latch having a spring actuated bolt comprised of two interchangeable halves.

This invention further contemplates a latch having a spring loaded bolt retractable by a swinging handle which in turn is spring loaded to always return and hold the handle in its normal inoperative position regardless of whether the bolt is fully projected or not.

In the drawings:

Figure 1 is a longitudinal section through the latch assembly.

20 Figure 2 is a plan view of the latch bolt.

Figure 3 is a side elevation of the latch bolt.

Figure 4 is a section along the line 4—4 of Figure 2.

25 Figure 5 is a section along the line 5—5 of Figure 3.

Figure 6 is an elevation of one of the two interchangeable parts comprising the bolt.

Figure 7 is a plan view of one of the interchangeable parts comprising the bolt.

30 Figure 8 is an end view of one part of the bolt.

Figure 9 is a plan view of a modified form of latch.

35 Figure 10 is a view along the line 10—10 of Figure 9.

Figure 11 is a section through the modified form of the bolt.

Figure 12 is a side elevation of the modified form of bolt.

40 Figure 13 is a detail of one part of the modified form of bolt.

The latch has an outer casing 1 and an inner casing 2. The inner casing 2 is provided with the ears 3 which carry the pin 4 upon which

45 the bolt retracting handle 5 is pivotally mounted. The casing 2 is provided with the bore 6 in which is slidably mounted the bolt 7. The bolt

7 is spring loaded by the coil bolt spring 8. The inner casing 2 is provided with the opening 9 for the rollback 10. The rollback 10 abuts against the forward end of the opening 9 as at 11 to limit the projection of the bolt.

The bolt 7 is composed of two identical interchangeable parts 12, shown in detail in Figures

55 6, 7 and 8. Each bolt part 12 is, roughly speaking, a semi-cylinder so that the two parts which

comprise the bolt form a cylindrical or round bolt. Each bolt part comprises a head portion

13 provided in its inner face with the recess 14 for the pin 15 which supports the roller 16. It

will be noted that the recess 14 for the pin 15 extends into but not completely through the bolt head 13 thus insuring concealment for the roller pin. Each bolt half 12 is provided with a rib 17 and a corresponding groove 18 running lengthwise of the bolt half. The forward portion of the bolt is likewise provided with a transverse opening 19 for the rivet 20. The bolt half 12 is provided with a recess 21 and a semi-cylindrical tail portion 22 having a shoulder 23.

To assemble the bolt the two identical interchangeable parts 12 are placed together so that the rib 17 of the one part 12 seats itself in the groove 18 of the other part and at the same time the pin 15 and roller 16 are mounted between the bolt head portions 13 with the ends of the pin 15 supported in the recesses 14. The bolt parts 12 are then riveted together with the rivet 20. The tail parts 22 of the bolt are fixed together by a washer 24 having a press fit with the shoulder 23. It will be seen that the recesses 21 of the bolt parts cooperate to form the rollback opening 25. It will be noted particularly in Figure 2 that the pin 15 which supports the roller 16 is completely concealed within the bolt head 13 thus giving the bolt head and roller a finished and neat appearance.

The pin 4 which supports the handle 5 also carries the flat U-spring having the spring ends 26 and 27, the spring end 26 extending downwardly through the opening 9 into the opening 25 in the bolt between the rollback 10 and the rear face 28 of the bolt opening 25. The hub portion of the handle 5 is provided with the radial slot 29 which accommodates the U-spring. As shown, the spring ends 26 and 27 are under tension or loaded. Hence, in case the bolt is not fully projected the U-spring will expand causing the rollback 10 to abut against the front face of the opening 9 as at 11 and thus cause the handle 5 to assume its normal non-bolt retracting position as shown in Figure 1.

In Figures 9 to 12 there is shown the modified form of the latch and bolt. In the modified form the latch bolt 31 is provided with the roller 32 and concealed roller pin 33 as in the principal form of the invention. In the modified form, however, though the bolt is comprised of two parts 34 and 35 which are riveted together by the rivet 36, the two parts 34 and 35 are not interchangeable. The part 34 of the bolt 31 is provided with the recess 37 and the other part 35 is provided with the projecting lug 38 which fits into the recess 37. In assembly the roller 32 and pin 33 are positioned between the two bolt parts with the ends of the pin 33 engaging in the concealed opening 39 and the lug portion 38 fitted in the opening 37, the two parts are then riveted together by the rivet 36.

It is evident from the above description that

there is herein set forth a novel latch and bolt construction wherein the projecting bolt head is provided with a roller supported upon a pin the ends of which are concealed within the bolt, 5 thus giving the projecting bolt head a neat and finished appearance. Further, the principal form of the invention is characterized in that the bolt is comprised mainly of two interchangeable or identical parts, either of which may be used instead of the other thus obviating the necessity for keeping the bolt parts separate thereby cutting down handling costs and in case the main bolt parts are die-cast, which is preferable although they may be otherwise fabricated, permits 10 both parts to be made from the same die thus cutting die costs.

I claim:

20. 1. A latch bolt having a bolt head, a roller mounted in the head and a pin for supporting the roller, the pin being concealed within the bolt head.
25. 2. A latch bolt having a bifurcated head, a roller mounted in the bifurcation, and a pin for supporting the roller, the ends of the pin projecting into and completely concealed within the bolt head.
30. 3. A latch bolt comprising a pair of members, means for fixing the members together, each member having a head portion spaced from the head portion of the other member and provided with a recess in its inner face, a roller positioned between the spaced head portions, and a pin for supporting the roller having its end portions seated in the recesses of the head portions of the said members, the said roller and cooperating head portions concealing the said pin.
40. 4. A latch bolt for a latch comprising a pair of members each having a head portion and a tail portion, means adjacent the head for securing the two members together, and a washer having a press fit with the tail portions of the said members to secure the tail portions together.
45. 5. A latch bolt for a latch comprising a pair of members each having a head portion and a tail portion, a rivet adjacent the head for securing the two members together, and a washer having a press fit with the tail portions of the said members to secure the tail portions together, the heads of the said bolt members being spaced from each other and each provided with a recess in its inner face, a roller positioned between the spaced heads of the bolt member, a pin supporting the said roller and having its ends seated in the recesses of the heads of the said members whereby the pin is concealed.
55. 6. A bolt for a latch comprising in combination a pair of similar interchangeable members, and means for securing the said members together.
60. 7. A bolt for a latch comprising a pair of interchangeable similar members each having a head portion with a recess in its inner face, a roller positioned between the inner faces of the head portions of the said members, and a pin for supporting the said roller, the ends of the pin being seated in the recesses of the head portions of the said bolt members whereby the pin is concealed from view.
70. 8. A bolt for a latch comprising a pair of similar interchangeable members, each of said members having a groove and a complementary rib, the rib of the one member being seated in the groove of the other member, and means for securing the two members together.
75. 9. A bolt for a latch comprising a pair of interchangeable similar members, each of said mem-

bers having a longitudinal groove and a complementary rib, the rib of the one member being seated in the groove of the other member, and means for securing the two members together.

10. A bolt for a latch comprising a pair of interchangeable similar members, each of said members having a groove and a complementary rib extending lengthwise of the bolt, and a shouldered tail portion, the rib of the one member being seated in the groove of the other member, and a washer having a press fit over the shoulders of the tail portions of the said bolt members to secure the members together. 80

11. A bolt for a latch comprising in combination a pair of members each having a head portion, the one member having a groove and the other a projecting portion interfitting in the groove of the other member, means for fixing the two members together, the head portions of the said members being spaced from each other and each having a recess in its inner face, a roller positioned between the head portions of the two members, and a pin for supporting the rollers having its ends engaging in the recesses in the head portions of the said members whereby the pin is concealed from view. 90

12. A latch comprising in combination a casing, a spring projected bolt slidably mounted in the said casing, the casing having an opening, and a pair of ears, a pin supported by the said ears, a handle having a rollback portion projecting through the opening in the casing for retracting the bolt, a spring mounted between the rollback and the bolt for holding the handle in its normal non-bolt retracting position when the bolt is only partially projected. 105

13. A latch comprising in combination a casing having an opening and a pair of ears, a spring projected bolt slidably mounted in the casing, a pin supported by the ears, a handle having a rollback portion projecting through the opening in the casing for retracting the bolt, the rollback portion being operatively connected to the bolt whereby the bolt holds the rollback in abutting relation with the wall of the opening in the casing when the bolt is fully projected, and a spring for holding the rollback in abutting relation with the wall of the said opening when the bolt is only partially projected whereby the handle is held in its normal non-bolt retracting position. 115

14. A latch comprising in combination a casing having an opening and a pair of ears, a spring projected bolt slidably mounted in the casing, a pin supported by the ears, a handle having a rollback portion projecting through the opening in the casing for retracting the bolt, the rollback portion being operatively connected to the bolt whereby the bolt holds the rollback in abutting relation with the wall of the opening in the casing when the bolt is fully projected, and a loaded U-spring mounted on the said pin having one end abutting against the handle and the other portion against the bolt for holding the rollback in abutting relation with the wall of the said opening when the bolt is only partially projected 130 whereby the handle is held in its normal non-bolt retracting position. 135

15. A latch bolt comprising a pair of members each having a head portion, a roller and pin for engaging the head portion, a longitudinal projection on one of the members which engages a longitudinal depression on the other member for aligning the parts, and means for securing the parts together. 145
